UNITED STATES PATENT OFFICE.

ROBERT PATON, OF CYNWYD, PENNSYLVANIA.

CALK ATTACHMENT FOR HORSESHOES.

1,016,708.

Specification of Letters Patent.

Patented Feb. 6, 1912.

Application filed October 6, 1911. Serial No. 653,184.

To all whom it may concern:

Be it known that I, ROBERT PATON, a citizen of the United States, residing at Cynwyd, Montgomery county, State of Pennsylvania, have invented a new and useful Calk Attachment for Horseshoes, of which the following is a specification.

My invention relates to detachable calk attachments for horseshoes, and it consists of improved means for clamping the adjustable frame carrying the calks, to the shoe.

It further consists of improved means for adjustably clamping the heels or quarters of the shoe.

15 It further consists of improved means for simultaneously moving the clamping members of the device.

It further consists of other novel features of construction, all as will be hereinafter 20 fully set forth.

The annexed drawings and the following description set forth in detail, one mechanical form embodying the invention; such detail construction being but one of various 25 mechanical forms in which the principle of the invention may be used.

In said annexed drawings:—Figure 1 represents a perspective view, seen from the underside of a horseshoe and my improved 30 calk attachment applied to the same. Fig. 2 represents a bottom plan view of parts of the attachment. Fig. 3 represents a detail view of one of the heel-clamps.

Similar numerals of reference indicate 35 corresponding parts in the figures.

Referring to the drawings, the numeral 1 indicates a horseshoe of the ordinary construction. The attachment has a plate, 2, into which a toe-calk, 3, is secured, and said 40 plate has upwardly and rearwardly projecting, inclined toe-clips, 4, which engage the toe of the shoe and of the horse's hoof. The plate has two rearwardly extending arms, 5, connected at their rear ends by a bridge-piece, 6, which is formed with a longitudinal, screwthreaded bore, 7. One portion, 8, of a right and left screw, 9, fits to turn in said bore and has a nut, 10, threaded upon it to serve as a lock-nut. The rear and op- 50 positely screwthreaded end, 11, of said screw is threaded into a threaded bore, 12, of a yoke, 13, and the flattened and perforated ends, 14, of two screw-arms, 15, are pivotally connected to the ends of the yoke 55 upon pins, 16, and have clips, 17, upon their

outer ends. Heel-calks, 18, are secured in said clips. The clips extend upward to engage the edges of the heels or quarters of the horseshoe. A washer, 19, and a nut, 20, fit upon each screw-arm to have the washer 60 bear against the inner edge of the heel or quarter of the shoe, and the nut serves to clamp the washer against the edge of the shoe which is thus clamped between the washer and the upturned lip, 21, of the clip. 65 The opening, 22, in the washer is of a somewhat greater diameter than the screw-arm, so that it may have sufficient play to find a square seat against the edge of the shoe. The screw has a polygonal end, 23, for the 70 application of a key or wrench for turning it.

When the device is to be attached to a horseshoe, the screw is rotated to unscrew its forward end from the bridge-piece of 75 the forward plate and to force the yoke to which the screw-arms are pivoted, rearward, thus spreading the frame and the clips. The washers and nuts have been moved inward to provide space for the heels of the shoe. 80 When now the device is applied to the foot and shoe of a horse, the clips will be at the outside of said shoe and, by rotating the right and left screw, the bridge-piece and plate and the yoke will be drawn together, 85 drawing the clips in upon the outer edges of the shoe. When said parts are sufficiently tightened, the lock-nut upon the forward end of the right and left screw is screwed up against the bridge-piece, locking the screw 90 against turning. The washers are now forced by the nuts against the inner edges of the shoe, thereby firmly clamping the heels or quarters of the shoe, and the horse is sharp-shod without removal of the shoe. 95

By providing the right and left screw to engage the bridge-piece of the toe-clip and the yoke for the heel-clips, said clips will be evenly drawn together from all sides at the same time, so that the device will have 100 an even grip at all points of contact with the shoe. The nuts and washers upon the screw-arms will clamp the heels of the shoe, thereby affording additional grip upon the shoe and insuring firm attachment of the 105 device upon the hoof and shoe.

Other modes of applying the principle of my invention may be employed for the mode herein explained. Change may therefore be made as regards the mechanism thus 110

disclosed, provided the principles of construction set forth respectively in the following claims are employed.

Having thus described my invention, what I claim as new and desire to secure by Letters Patent, is:—

1. In a calk attachment for horseshoes, a toe-plate provided with a toe-clip and a toe-calk, a screw rotatably connected to said plate, a yoke having a longitudinal threaded bore for said screw, screw-arms pivoted to said yoke and having heel-clips and heel-calks at their outer ends, washers upon said arms and adapted to bear against the inner edges of the shoe, and nuts threaded upon the screw-arms and bearing against said washers.
- 15 2. In a calk attachment for horseshoes, a

toe-plate provided with a toe-clip and a toe-calk, a screw rotatably connected to said plate, a yoke having a longitudinal threaded bore for said screw, screw-arms pivoted to said yoke and having heel-clips and heel-calks at their outer ends, washers upon said arms and adapted to bear against the inner edges of the shoe, and nuts threaded upon the screw-arms and bearing against said washers. 20

ROBERT PATON.
